UNITED STATES PATENT OFFICE.

MATTHEW HENDERSON, OF AUCKLAND, NEW ZEALAND.

TRAMWAY TROLLEY POLE.

Application filed March 29, 1924. Serial No. 702,932.

To all whom it may concern:

Be it known that MATTHEW HENDERSON, a subject of the King of Great Britain, residing at Selwyn Street, Onehunga, in the city of Auckland, Provincial District of Auckland, Dominion of New Zealand, has invented certain new and useful Improvements in or Relating to Tramway Trolley Poles, of which the following is a specification.

This invention relates to improvements in connection with the trolley poles of electric trams and like vehicles which are worked on the overhead system, and has particular reference to that kind of mechanism which automatically relieves the tension from the trolley pole should the trolley, from any cause, jump off the overhead wire.

The object of my invention is to prevent damage and delay to the service when the trolley leaves the overhead wire, the momentum with which the pole is jerked upwards being sufficient to break down the supporting wires above or cause a jamming of the trolley amongst same.

The particular improvement aimed at in my invention is to provide a simple automatic release of the pole from the main tension spring or springs, when the trolley leaves the overhead wire, and allow the trolley and pole to fall by gravity and without recoil clear of the overhead wires, after which it may be conveniently reset by the guard or other person in charge.

Existing mechanisms for this purpose are too expensive to manufacture and are too complicated in use.

The invention will be further illustrated with reference to the accompanying drawings, where—

Figure 1 shows a side elevation of the mechanism in working position on the overhead wire.

Figure 2 is a plan of same.

Figure 3 is a partial side elevation showing the crosshead in section on line AB Figure 4.

Figure 4 is an end elevation of Figure 1.

Figure 5 is a side elevation showing the mechanism in the reinstating position.

In the different views the same reference letters and figures refer to like parts.

In the construction shown on the drawings, the tension on the trolley pole is effected by the spring 1, the lower end of the trolley pole being connected to a stirrup

piece 4 which is fulcrumed at 11 to the swivelling base 5, the latter being pivoted on the standard 6 which is secured to the roof of the car.

This is a similar construction to that at present in use, the upward tension of the trolley pole on to the wire being maintained by means of one or more springs transmitting their tension through a pair of tension rods operating on pivot pins fixed to the stirrup piece, the tension spring surrounding an extending arm secured to the swivel base, a stop nut or nuts being fixed at the outer ends of the arm to limit the travel upwards of the pole when the trolley leaves the overhead wire.

The improvement in my invention consists in means whereby these tension rods are automatically disconnected from the sliding plate or crosshead upon which the tension springs bear when the trolley leaves the overhead conductor, after which the pole and trolley are free to fall by gravity a sufficient distance to clear the overhead wires and prevent damage by jamming or fouling same.

A further improvement provides for taking up the recoil after the trolley pole has fallen clear of the overhead wire and with means whereby the apparatus can be reset to the working position by the conductor or motorman in charge.

To accomplish this, the tension rods 10 are pivotally connected to pins 12 projecting from the sides or cheeks of the stirrup piece 4. The other ends of the tension rods are screwed and nutted at 13 so as to transfer the tension from the sliding crosshead 8, which latter has two slots 14 in the underside for the reception of the bolts 10.

The slots 14 terminate in countersunk recesses 15, one of the nuts 13 having a projection thereon to seat into the recess. A pair of bell crank shaped levers 16 are keyed or otherwise securely connected one at each side to the fulcrum pin 11, the upper ends of the levers being stayed together as an integral unit to prevent distortion. This may be done by a suitable distance piece which is here shown as a bolt 17 shouldered, screwed and nutted at both ends on to the bell crank levers. Instead of keying the levers 16 to the pin 11 they could, if preferred, be formed integral with the stirrup piece 4. The pin 12 transfers motion from 4 to 16,

A pair of recoil rods 19 are pivotally connected at one end as shown at 20 to the bell crank levers. The forward ends of the recoil rods are passed through holes 21 in the sliding crosshead 8, the ends being screwed and having a pair of nuts 22 fitted thereto at a suitable distance from the ends so that when the trolley pole falls to the recoil position as shown by Figure 3, these 10 nuts transmit the weight and shock from the falling pole to the main tension spring 1, preventing the pole falling beyond the recoil position.

When the trolley pole is in its normal 15 working position, with the trolley on the overhead wire, the nuts 22 stand quite clear of the face of the crosshead 8, as they are not required to operate until the pole is falling after being released.

20 When the pole arrives to the position shown in Figure 3, ordinarily a violent upward recoil of the pole 2 would take place from the sudden compression of the spring 1, but this is prevented by fitting a bracket 23 to the tension rods 10 so that when the spring 1 is compressed by the falling of the pole, the buffer piece 26 secured to the bracket 23 falls on to the arm 9 between the end face of the nut 27 and the sliding crosshead 8.

The bracket 23 with stop piece 26 attached thereto may be made of any suitable shape and secured by convenient means to the tension rods.

35 The arrangement as shown on the drawings herewith shows 23 formed to a U shape, the lower ends being secured to the tension rods 10 by nuts 24 at each side. The top of the U piece is bent over at 25 at right angles carrying the buffer 26 as shown. When the trolley pole is in its working position as shown in Figure 1, the buffer 26 is clear of the circular portion of the nut 27 and the top of the crosshead 8 as shown.

40 If the trolley should leave the wire 3 from any cause, the trolley pole 2 flies upwards with considerable force, and when the crosshead 8 strikes the face of the stop nut 27 on the extending arm 9, the tension rods 10 are released from the slots 14.

45 This is accomplished by the upward momentum of the trolley pole 2 after crosshead 8 strikes the nut 27 which releases the countersunk nuts 13 from the recesses 15, allowing the rods 10 to fall by gravity, when the buffer 26 falls on the outer periphery of the nut 27 until the pole 2 reaches the recoil position shown in Figure 3, when it falls in between 8 and 27 to prevent recoil as previously described.

50 The lower arms of the bell crank levers 16 have resetting pins 30 fitted thereto, so that when the trolley pole is pulled down approximately to a horizontal position as shown in Figure 5, the pins 30 lift the ten-

sion rods 10 up into the slots and the countersunk seats in the crosshead 8 to their normal working position, when the trolley can be reset on to the wire 3 in the ordinary manner.

55 The action of resetting the tension rods in their seats will be better understood by reference to Figure 3, when it will be readily seen that on pulling the pole 2 further down so as to reinstate rods 10 by lifting pins 30, the travel of crosshead 8 is more rapid than the travel of nuts 13, which facilitates the insertion of the latter into the recesses 15.

The pins 30 are preferably shouldered, 60 screwed and nutted to secure to the lower arm 29 of the bell crank lever 16, and to facilitate adjustment, the extending portion 30 could be turned eccentric with the shouldered and screwed portion which fits through the hole in the arm 29.

65 The crosshead 8 is prevented from turning on the extending arm 9 by a feather key 32 fitting in the crosshead 8 sliding in the keyway 31.

70 The recoil rods 19 can have a knuckle joint 33 fitted in a suitable position as shown to convert reciprocating motion at the crosshead end into partial rotary motion at the bell crank lever end.

I claim:

75 1. A trolley pole safety release for electric trams and the like, consisting, in combination with the usual tension springs and trolley pole, of a stirrup piece fulcrumed to a revoluble base pivoted to an upright column, of a pair of tension rods to hold the pole on the overhead wire, the rods each having one end pivoted to the stirrup piece at the foot of the pole and the other end detachably fixed to the sliding crosshead by 80 nuts on the rods, one of the said nuts on each rod having a conical shaped projection thereon to seat in a recess at the end of the slots in the crosshead so that when the trolley leaves the wire and the pole is jerked upwards, it is released from tension and allowed to fall clear of the overhead wire by releasing the tension rods from the crosshead immediately the tension spring strikes the stop nut on the end of the spring arm, substantially as described and as shown in the drawings.

85 2. In a trolley pole safety appliance, a pair of bell crank levers which may be separate from or integral with a stirrup piece, but pivoted to the fulcrum pin of the pole, a distance piece holding together the upper ends of the arms of the levers, a pair of resetting pins fixed to and projecting from short arms of the levers, a pair of recoil rods pivoted at one end to the bell crank levers and to a knuckle joint near the crosshead at the other end, the rods being continued through holes in the cross-head and nutted on the outer ends to facilitate ad-

justment for transferring the weight of the falling pole on to the main spring substantially as described and as shown on the drawings.

5. 3. In a trolley pole safety appliance a recoil buffer hanging from a bracket secured to the tension rods so that when the latter are released from the tension of the spring, the buffer is free to fall on to the 10 stop nut at the end of the spring arm, after which it falls in between the crosshead and the stop nut when the spring is compressed by the falling pole to the recoil position substantially as described and as 15 shown on the drawings.

4. The combination in a safety trolley pole release of the various parts as claimed in claim 1, all working together to produce an automatic release of the tension rods 20 when the trolley leaves the overhead wire, means for arresting the fall of the pole and preventing recoil of same with facility for resetting the tension rods to the working position again all substantially as shown and

described with reference to the accompanying drawings. 25

5. The combination in a safety trolley pole release of the various parts as claimed in claim 2, all working together to produce an automatic release of the tension rods 30 when the trolley leaves the overhead wire, means for arresting the tail of the pole and preventing recoil of the same with facility of resetting the tension rods to the working position again. 35

6. The combination with a safety trolley pole release of the various parts as claimed in claim 3, all working together to produce an automatic release of the tension rods when the trolley leaves the overhead wire, 40 means for arresting the tail of the pole and preventing recoil of the same with facility for resetting the tension rods to the working position again. 45

In testimony whereof I affix my signature.

MATTHEW HENDERSON.
